UNITED STATES PATENT OFFICE.

CHARLES E. SMITH, OF NIAGARA FALLS, NEW YORK, ASSIGNOR TO THE SHREDDED WHEAT COMPANY, OF NIAGARA FALLS, NEW YORK.

MEANS FOR MANUFACTURING FILAMENTOUS BISCUIT.

1,194,341.

Specification of Letters Patent. Patented Aug. 8, 1916.

Application filed January 11, 1912. Serial No. 670,691.

To all whom it may concern:

Be it known that I, CHARLES E. SMITH, a citizen of the United States, and resident of Niagara Falls, in the county of Niagara and State of New York, have made a certain new and useful Invention in Means for Manufacturing Filamentous Biscuit; and I declare the following to be a full, clear, and exact description of the same, such as will 5 enable others skilled in the art to which it appertains to make and use the invention, reference being had to the accompanying drawings, and to letters or figures of reference marked thereon, which form a part of 10 this specification.

Figure 1 is a side view of a reducing machine showing the invention. Fig. 2 is a transverse section on the line 2—2 of Fig. 1 through the exhaust chamber. Fig. 3 is a 20 transverse section enlarged showing the pressure roll and belt link. Fig. 4 is a side view showing the same.

The invention has relation to means for manufacturing filamentous biscuit of thin or 25 wafer-like character, and it consists in the novel construction and combinations of devices, as hereinafter set forth.

The object of the invention is to provide 30 means whereby a thin band of piled filaments can be pneumatically operated upon, to facilitate the deposit of wafer-like biscuit forms upon a receiver for baking.

In the accompanying drawings, illustrating 35 a form of this invention, the letter A designates reducing mechanism whereby the grain, properly softened by water and cured, is reduced to filaments, which are piled in 40 layer form upon a bandlike moving receiver B, whereon the layer of piled filaments is somewhat compressed by means of a roller C, divided into biscuit form, and carried into a pneumatic chamber D, wherein the 45 biscuit forms are first held up by means of an exhaust, as at E and are then deposited upon a receiving pan or baking device F.

The grain having been softened, by soaking, boiling or steaming, and partially dried or cured to equalize the consistency of the exterior coats and interior portion of each 50 kernel, is carried to the reducing mechanism, which involves steel rolls a, having small circumferential grooves, from which the material is discharged by small steel strips or fingers b, upon a moving belt or receiver B. 55 Usually this belt is made of links and is

designed to have a movement of corresponding speed to that of the reducing rolls, so that the filaments of grain which are taken by the steel fingers from the grooved rolls are laid upon the receiver in band form and in parallel relation. These filaments are piled upon the receiver to a thickness sufficient for the production of a thin biscuit or cracker, the band of filaments produced being from about 10 to 15 filaments deep. 60 Owing to the limited number of filaments piled upon each other in the formation of the band, it is quite open in structure and freely pervious to air, and means are employed to condense or close substantially the 65 interstices of the band, as well as to decrease its thickness, to render the band capable of being lifted by the exhaust hereinafter referred to, said means consisting preferably of a cylindrical roller C. The roller C is 70 provided with a shaft d, the journals of which are located in bearings in oblique arms n, at the sides of the framing in which the link belt travels. These arms n, are pivoted to a transverse bar having reversely 75 directed horizontal arms p, the ends of which have delicate adjustment between set screws r, and s, arranged respectively in upper and lower seats of uprights t, secured to the sides of the frame. 80

The receiver or belt carrying the band of filaments passes under the roller C to and through a chamber D, in connection with an exhaust pipe and provided with valve mechanism f, whereby an intermittent operation of the exhaust is effected. Before entering the exhaust chamber the band of filaments is pressed down and leveled on its upper surface by the roller C above referred to. It is also subdivided transversely by 85 means of transverse ribs of the links and transverse ribs of cutting or punching belts indicated at G.

As the conveyer belt enters the chamber D, its links come under the operation of the exhaust, which is designed to lift the biscuit from the links and cause them to adhere to the links m, of a belt G, passing through the exhaust and moving at the same rate of speed with the conveyer belt. These links 100 m, are designed to be provided with perforations, through which the exhaust takes effect. After a sufficient number of biscuits 105 have been lifted from the conveyer belt to the exhaust belt, the exhaust is shut off 110

momentarily and the biscuit are dropped upon a receiving pan or baking iron, whereon they are designed to be cooked. While the biscuits are being conveyed into the exhaust chamber, the receiving pan is moved transversely to a distance sufficiently wide to receive a second row of biscuits at the next shut-off of the exhaust, which is designed to operate intermittently.

10 Having described my invention, what I claim as new and desire to secure by Letters Patent is:

1. In a machine of the character described, a movable carrier, means for reducing grain to filamentous form and depositing the same upon said carrier in a structurally open layer, means coöperating with said carrier to press the filaments together and substantially close the interstitial openings thereof, and an intermittent exhaust device for lifting the layer having its interstitial openings so closed, carrying the said layer forward and dropping the same.

2. In a machine of the character described, a movable carrier, means for reducing grain to filamentous form and depositing the same upon said carrier in a structurally open layer, means coöperating with said carrier to press the filaments together and substantially close the interstitial openings

thereof, including a roller having upper and lower micrometric adjustment means to hold said roller fixedly spaced from said carrier, and an intermittent exhaust device for lifting the layer having its interstitial openings so closed, carrying the said layer forward and dropping the same.

3. In a machine of the character described, a movable carrier, means for reducing grain to filamentous form and depositing the same upon said carrier in a structurally open layer, means coöperating with said carrier to press the filaments together and substantially close the interstitial openings thereof, including a roller, pivotal arms carrying said roller, a lever upon the pivot rod of said arms, and upper and lower screws engaging the outer end of said lever for micrometric adjustment of said roller and to hold the roller fixedly spaced from said carrier, and an intermittent exhaust device for lifting the layer having its interstitial openings so closed, carrying the said layer forward and dropping the same.

In testimony whereof I affix my signature, in presence of two witnesses.

CHARLES E. SMITH.
